C. Brown & Co.

UNITED STATES PATENT OFFICE.

ALVA L. KITSELMAN, OF RIDGEVILLE, INDIANA.

DESIGN FOR A WIRE FENCE.

SPECIFICATION forming part of Design No. 29,158, dated August 2, 1898.

Application filed January 26, 1898. Serial No. 668,078. Term of patent 7 years.

To all whom it may concern:

Be it known that I, ALVA L. KITSELMAN, a citizen of the United States, residing at Ridgeville, in the county of Randolph and State of Indiana, have invented a new and original Design for a Wire Fence, of which the following is a specification.

This invention relates to a new and original design for a wire fence; and it has for its object to provide a design of this character that shall be both useful and ornamental.

The leading feature of the design resides in a wire fence having a series of horizontal parallel twisted cables and a series of twisted cross-wires interwoven with the cables and certain of which cross-wires are crossed in **X** form at one side of the intermediate cable and are provided with straight portions extending across the space at the opposite side of said intermediate cable, the remaining cross-wires being straight from end to end and bisecting the diamond spaces between said **X**-shaped figures, all of said cross-wires having their straight portions at one side of the intermediate cable closely arranged together in groups of three parallel strands forming the sides of oblong rectangular spaces.

In the drawing the figure is a plan view or elevation of a section of wire-fence pattern embodying the herein-described design.

Referring to the drawing, the numeral 1 designates the horizontal parallel twisted ca-

bles running lengthwise of the fence-pattern, and these cables have interwoven therewith the twisted cross-wires 2. Certain of these cross-wires at one side of the intermediate cable 1 are crossed to form the **X**-shaped figures 3 and are also provided with straight portions 4, which extend across the space at the opposite side of said intermediate cable. The remaining cross-wires (designated by the numeral 5) are straight from end to end and intersect all of the cables and are so arranged as to bisect the diamond-shaped spaces between the **X**-shaped figures 3. The said straight cross-wires 5 also extend between the straight portions 4 of the other cross-wires, whereby all of the cross-wires have their straight portions at one side of the intermediate cable closely arranged together in groups of three strands, which groups of strands form the sides of oblong rectangular spaces 6.

What I claim is—

The design for a wire fence, herein shown and described.

In testimony that I claim the foregoing as my own I have hereto affixed my signature in the presence of two witnesses.

ALVA L. KITSELMAN.
